UNITED STATES PATENT OFFICE.

KATHARINE G. TOWNSEND, OF NEW YORK, N. Y.

HOLDER FOR TELEPHONE-RECEIVERS.

Specification of Letters Patent. Patented Dec. 18, 1917.

1,250,716.

Application filed January 27, 1917. Serial No. 144,850.

To all whom it may concern:

Be it known that I, KATHARINE G. TOWNSEND, a citizen of the United States, and a resident of New York, in the county of New York and State of New York, have invented 5 certain new and useful Improvements in Holders for Telephone-receivers, of which the following is a specification.

My invention has for its object the production of a holder for telephone receivers which shall be simple in construction, of low cost to manufacture and by means of which the receiver may be placed in close proximity to the ear of the wearer of the device thus enabling the wearer to hear the telephone conversation perfectly while permitting him the free use of both hands.

A further object of the invention is the production of a device of the character above described which shall have means adapted to permit a variation or adjustment of the vertical position of the receiver as well as means adapted to permit a variation or adjustment of the horizontal position of the same to suit the convenience of the wearer.

A further object of the invention is the construction of a device of the character above described which shall have means for supporting the receiver in operative position without the necessity of actually fastening or strapping the receiver to the device.

To the above ends my invention consists in the novel construction of holder for telephone receivers hereinafter more particularly described and then specified in the claims.

In the drawings:

Figure 1 is a vertical cross-section (partly in elevation) of my improved holder taken 40 on the line 1—1 of Fig. 2.

Fig. 2 is a side elevation of the holder showing the receiver supported thereby and in operative position.

Fig. 3 is an enlarged side elevation of the 45 pivot for holding the supporting piece for the receiver to a rod adapted to telescope within a hollow standard to be presently described.

Fig. 4 is a horizontal cross-section of the 50 rod referred to in Fig. 3.

Referring more particularly to the several figures of the drawing in which like figures of reference refer to corresponding parts in all the views:

55 1 indicates a yoke adapted to fit over a shoulder of the wearer of the device, the

arms or sides thereof extending downwardly over the chest and back of the wearer and preferably conforming in shape to the figure of the wearer. I preferably construct the 60 yoke of a spring sheet metal so that the sides thereof will firmly grip the body of the wearer of the device and thus firmly hold the same in position on the shoulder. In some cases, however, the device may be held 65 in position by means of a chain 1', as is illustrated, which is fastened to the lower end of one of the sides of the yoke and which is adapted to be passed under the arm of the wearer and then fastened to a hook on the 70 end of the other side of the yoke. If so desired and for the purpose of securing lightness in weight said sides may be cut out as at 2, 3 as is illustrated. Mounted on said yokes 75 1 and securely fastened thereto is a hollow standard 4 having a vertical slot 5 cut in the wall thereof.

6 indicates an elongated U-shaped supporting piece enlarged at one end and adapted to receive and support the barrel of a 80 telephone receiver 7, said U-shaped supporting piece conforming in shape to the shape of the barrel of the receiver so that the receiver may be fit snugly therein. If so desired, said supporting piece may be 85 made of a spring metal so as to firmly grip the receiver. To secure lightness in weight the body portion of the supporting piece is preferably cut away as at 8. Fastened 90 to said supporting piece 6 are the downwardly extending ears 9 pivotally mounted on a rod 10 and held thereto by a pivot 11 extending through said ears and through a hole 12 passing transversely through said rod 10. The end of said pivot 11 is screw-threaded as shown and is adapted to receive a nut 13 the loosening of which will permit the turning of the supporting piece 6 on the pivot 11 in order to regulate or adjust the horizontal position of the supporting 100 piece 6 when desired. To prevent the turning of the pivot 11 when the nut 13 is loosened or tightened, a recess 14 (Fig. 4) is cut in the body of the rod 10, said recess being adapted to receive the lug 15 secured 105 to the pivot 11.

The rod 10 is adapted to telescope within the standard 4 and is provided with a screw-threaded hole 16 for receiving the shank of the thumb-screw 17 which passes through 110 the slot 5. Obviously, the vertical position of the U-shaped supporting piece 6 may be

varied or adjusted by loosening said thumbscrew 17 and raising or lowering said supporting piece to the height desired.

I am aware that various forms of head-gear have been proposed to accomplish in a measure only the results attained by the practice of my invention and which permit the wearer the free use of both hands while carrying on his conversation but these devices aside from being unsightly and cumbersome, are objectionable in that because of their weight in some cases, and because of the firmness with which they clasp the head on others, they produce fatigue and headache. It will be understood from the foregoing description that my device is not a head-fastening in any sense of the word. In fact no part of the device is fastened to or contacts with the head of the wearer so that the head may be turned or moved away from the receiver and from the device when so desired.

It will also be manifest from the foregoing description that the receiver rests in the U-shaped supporting piece and is held in operative position thereby without the necessity of employing straps or clamps or any fastening devices so that the receiver may be easily and expeditiously placed in position or removed. Also the position of the supporting piece 6 may be so adjusted by means of the vertical and horizontal means hereinbefore described that the head of the telephone receiver may be brought into as close proximity with the ear of the wearer of the device as is desired. When the supporting piece is turned at an angle from the horizontal the receiver is prevented from slipping out of its supported or operative position by means of the shoulders which are present on the ends of the con-

ventional form of receiver, which ends will engage the ends of the supporting piece 6.

It will be understood that my invention is not limited to the exact and precise details of construction herein shown and described such being for the purpose of illustration only, but various modifications may be resorted to without departing from the spirit of the invention as set forth in the appended claims.

What I claim as my invention is:—

1. In a holder for telephone receivers, a yoke having spring sheet metal arms adapted to extend downwardly over the back and chest of the wearer and to grip the body of the wearer, an elongated U-shaped support pivoted to said yoke for supporting the barrel of the telephone receiver and adapted to be rocked on its pivot in a vertical plane to vary the height of the head of said receiver and means for adjusting the vertical position of said support.

2. In a holder for telephone receivers, a yoke having sheet metal arms adapted to extend downwardly over the back and chest of the wearer, a standard mounted on said yoke, a rod adapted to telescope in said standard, a U-shaped support pivoted to said rod for receiving and supporting the telephone receiver, means for adjusting the vertical position of said support and a chain fastened to one of the arms of said yoke and adapted to be detachably secured to the other of said arms.

Signed at New York, in the county of New York and State of New York, this 24th day of January, A. D. 1917.

KATHARINE G. TOWNSEND.
